HOBBYHORSE

Charlie A. Batten, College Park, Md.

Application March 6, 1953, Serial No. 23,940

Term of patent 14 years

(Cl. D34—15)

To all whom it may concern:

Be it known that I, Charlie A. Batten, a citizen of the United States, and a resident of College Park, in the county of Prince Georges, State of Maryland, have invented a new, original, and ornamental Design for a Hobbyhorse, of which the following is a specification, reference being had to the accompanying drawing, forming a part hereof.

In the drawing,

Figure 1 is a perspective view of a hobbyhorse, showing my new design;

Fig. 2 is a side view of the reverse side of the hobbyhorse, shown in Figure 1;

Fig. 3 is a top plan view of the hobbyhorse, shown in Figure 1; and

Fig. 4 is a front end view of the hobbyhorse, shown in Figure 1.

My new hobbyhorse design is characterized by the arrangement of the horse's head and chest,

in conjunction with the seat portion and its associated S-shaped support.

I claim:

The ornamental design for a hobbyhorse, as shown and described.

CHARLIE A. BATTEN.
